DESIGN FOR A SEAT FOR BICYCLES AND THE LIKE

William I. Smith, Perrysburg, Ohio, assignor to
The Hettrick Manufacturing Company, Toledo,
Ohio, a corporation of Ohio

Application November 13, 1947, Serial No. 142,509

Term of patent 14 years

(Cl. D90—16)

To all whom it may concern:

Be it known that I, William I. Smith, a citizen of the United States and a resident of Perrysburg, Wood County, Ohio, have invented a new, original, and ornamental Design for a Seat for Bicycles and the like, of which the following is a specification, reference being had to the accompanying drawing, forming a part thereof.

In the drawing:

Figure 1 is a top plan view of the seat for bicycles and the like, showing my new design;

Figure 2 is a side elevation of the seat for bicycles and the like;

Figure 3 is a front end elevation of the seat for bicycles and the like;

Figure 4 is a transverse section on the line 4—4 of Figure 1; and

Figure 5 is a longitudinal section on the line 5—5 of Figure 1.

I claim:

The ornamental design for a seat for bicycles and the like, as shown.

WILLIAM I. SMITH.
